(57) **CLAIM**

The ornamental design for a digital notebook, as shown and described.

DESCRIPTION

FIG. 1 is a front perspective view of a digital notebook with a cover open according to a first embodiment of my new design;

FIG. 2 is a rear perspective view thereof;

FIG. 3 is a front perspective view of the digital notebook of FIG. 1 with the cover closed;

FIG. 4 is a front elevational view of the digital notebook of FIG. 1;

FIG. 5 is a rear elevational view thereof;

FIG. 6 is a top plan view thereof;

FIG. 7 is a bottom plan view thereof;

FIG. 8 is a right side elevational view thereof;

FIG. 9 is a left side elevational view thereof;

FIG. 10 is a partial front perspective view of a portion of the digital notebook indicated in FIG. 1;

FIG. 11 is a partial front elevational view of a portion of the digital notebook indicated in FIG. 4;

FIG. 12 is a front perspective view of a digital notebook with a cover open according to a second embodiment of my new design;

FIG. 13 is a rear perspective view thereof;

FIG. 14 is a front perspective view of the digital notebook of FIG. 12 with the cover closed;

FIG. 15 is a front elevational view of the digital notebook of FIG. 12;

(Continued)

FIG. 16 is a rear elevational view thereof;
 FIG. 17 is a top plan view thereof;
 FIG. 18 is a bottom plan view thereof;
 FIG. 19 is a right side elevational view thereof;
 FIG. 20 is a left side elevational view thereof;
 FIG. 21 is a partial front perspective view of a portion of the digital notebook indicated in FIG. 12; and,
 FIG. 22 is a partial front elevational view of a portion of the digital notebook indicated in FIG. 15.
 The dot-dot-dash broken lines indicate the boundary of the enlarged portions of the drawings. The remaining broken lines in the figures depict portions of the digital notebook. The broken lines form no part of the claimed design.

1 Claim, 18 Drawing Sheets
